CLARENCE S. DAVIS, OF BUFFALO, NEW YORK, ASSIGNOR TO THE DAVIS METAL TIE & RAIL CLAMP CORPORATION, OF BUFFALO, NEW YORK, A CORPORATION OF NEW YORK

METALLIC RAILWAY TIE AND ASSOCIATED PARTS

Application filed March 27, 1929. Serial No. 350,804.

My invention relates to metallic railway ties and associated parts, and has for its object the provision of a metal tie having a rail seat, of a dimension transversely, sufficient to provide the proper seating for a rail resting thereon and a supporting base of greater transverse dimension than said rail seat so as to provide proper support for the tie upon the road bed; the combination of a rail seat of definite transverse dimension and a wider supporting member enabling the rail to be made comparatively light in weight without detracting from its supporting qualities and rigidity.

Another object of my invention is to provide a metallic tie having a rail-seating member and a supporting member connected by a web and having the supporting member provided with anchors along its length, preferably disposed in planes at opposite sides of said web.

Another object of my invention is the provision of new and novel means for securing the rails of a railway track to the ties; and to otherwise improve on metallic ties and rail securing accessories thereto.

The invention consists in the novel features of construction and in the arrangement and combination of parts to be hereinafter described and more particularly pointed out in the subjoined claims.

In the drawings:—

Fig. 1 is a perspective view of a section of a railway track showing a number of my improved ties supporting the rails thereon, and my improved securing means for securing the rails to said ties.

Fig. 2 is an enlarged transverse section through the track, taken on line 2—2, Fig. 1.

Fig. 3 is a longitudinal section, taken on line 3—3, Fig. 2.

Fig. 4 is an enlarged longitudinal section, taken on line 4—4, Fig. 2.

Fig. 5 is an enlarged horizontal section taken on line 5—5, Fig. 1.

Fig. 6 is a transverse section through one of the ties taken on the same plane as the metallic tie shown in Fig. 4.

Fig. 7 is a detached perspective view of one end of one of the splice members em-

ployed for securing adjacent ends of two rail sections together.

Fig. 8 is a horizontal section taken on line 8—8, Fig. 4, looking in the direction of the arrow crossing said line.

Fig. 9 is a detached perspective view of one of the wedging lock-pins.

Fig. 10 is a perspective view showing a portion of my improved metallic tie, a rail mounted thereon, a modified form of rail clamp, and means for securing said clamp to the tie in rail-retaining position.

Fig. 11 is a perspective view similar to Fig. 10, showing a further modified form of my invention.

Fig. 12 is a section taken on line 12—12, Fig. 11.

Fig. 13 is a detached perspective view of one of the retainer yokes employed in the several forms of my invention.

Reference being had to the drawings in detail, 15 designates the metallic ties which are of substantially I-formation, each tie comprising an upper rail-seating member 16, a comparatively wide supporting member 17 parallel with said rail-seating member, and a central vertically-disposed web 18 connecting the members 16 and 17.

The rail-seating member 16 comprises two flanges extending laterally in opposite directions from the upper edge of the vertical web 18, while the supporting member 17 consists of two somewhat wider flanges extending laterally in opposite directions from the lower edge of said web.

Through each of the flanges forming the supporting member 17, which may also be termed a "rest", openings 19 are punched and the metal from these openings bent downwardly to form anchor ears or lugs 20, 21. The anchor ears or lugs 20 are stamped from the flange at one side of the web, while the anchor ears or lugs 21 are stamped from the flange at the other side of the web of each tie; the anchor ears or lugs 20, 21, being preferably in different planes along the length of the tie and staggered, as clearly shown in Fig. 2. These anchor ears or lugs, more generally referred to as "anchors", are preferably formed as stated, 100

but may be in the form of depending members on the rest secured thereto by welding, riveting, or otherwise.

The ties are placed on or in the roadbed, and the anchors 20, 21 forced into the roadbed, serving to prevent lengthwise movement of the ties, or movement transversely with respect to the direction of the track supported on the ties.

10 The rails of the track are designated by the numeral 22, and in Figs. 1 and 5, the abutting ends of two rail lengths or sections are shown. These rail lengths or sections are connected together by my improved splice members 23, said splice members overlying adjacent ends of two sections. The rails, between the ends thereof, are connected to the ties by means of clamp members 24. The sections of the rails abut over the center of a tie and the splice members 23 are seated upon three ties bridging the spaces between said ties. Each splice member has an outer flat portion 25 which lies upon three of the ties, as stated, and an inner portion 26 conforming in shape to the web and flange at each side of the rail 22. The inner portions 26 of said splice members bear against opposite sides of the web of a rail and against the two flanges thereof, the edges of said flanges being in contact with shoulders 27 formed on the undersides of said splice members. These splice members are secured to the rail in the usual manner by means of bolts 28 and nuts 29 applied to said bolts, and they are provided at their edges with angular retainer lugs 30, which are passed through openings 31 in the two flanges forming the seating member 16 of each tie. The retainer lugs 31 are arranged in pairs spaced at regular intervals along the splicing members, and therefore determine the spacing of the ties on which said splicing members are seated.

45 In placing the splicing members in position on the ties, it is necessary to enter the angular retainer lugs 30 through the openings 31, after which the splice members may be swung inwardly and downwardly against the web and flanges of the rail. This will bring the bolt holes in said splice members into registration with the usual elongated bolt holes in the rail and permit the securing bolts 28 to be fastened thereto.

55 As is common in railway construction work of this kind, the nuts 29 bear against lock washers 32, which in turn are forced by the nuts 29 against the up-standing or web-bearing portions 33 forming part of the inner portions 26 of the splice members.

60 The ends of the angular retainer lugs 30 bear against the undersides of the flanges forming the seating members of the ties, and they serve to fasten the splice members to the ties and prevent movement of the ends of the rail sections laterally. They also 65 prevent movement of said ends in a vertical

direction so long as the nuts 29 on the bolts are properly tightened. However, under continual use and heavy traffic over the rails, the vibration of the track structure, including the rails, the ties, and the connecting mediums, will eventually cause the nuts to become loosened, and the retainer lugs at the outer edges of the splice members, when used alone to secure the splice members to the ties under such conditions, would be insufficient to prevent slight vertical movement of the rails on the ties, which would result in a slight tilting of the splice members with the angular retainer lugs as fulcrums for the same. To guard against this, I employ retainer yokes or yoke-like fastener members 34, which are constructed of bar material. Each yoke or fastener member comprises a horizontal portion 35 and two depending portions or legs 36 at opposite ends of the horizontal portion. Formed in each of these legs is a key hole 37, the key hole in one of said legs being disposed in a lower plane than the key hole in the other, and these key holes are preferably of oval formation with their greater dimension disposed in a vertical plane.

70 In the preferred form of my invention, the legs 36 of the fastening members 34 are passed downwardly through openings 38 formed in the flat portions 25 of the splice members, and through registering openings 39 in the opposite flanges of the seating member 16 of the tie. Thus positioned, the horizontal portions 35 of said fastener members bear against the flat portions 25 of said splice members, and these horizontal portions are drawn down firmly and securely against said flat portions by means of tapering or wedge lock keys 40 passed through the key holes 37 in said fastener members and through an opening 41 in the web of the tie 15 alined with said openings 37.

75 Each of said tapering or wedge lock keys 40 is round in cross section, and slit at its smaller end, as at 42. The lock keys are 80 passed through the key holes 37 and the openings 41 in the web of the tie, and are driven firmly in place so as to draw the fastener members 34 securely against the upper surfaces of the flat portions 25 of the splice members.

85 Where the flanges forming the seating member of a tie are gradually thickened from their outer edge toward the web 18, these flanges are gouged out in any suitable manner, as at 43, Fig. 6, so as to provide long bearings for the lock keys, the gouged-out portions forming continuations of the openings 41 in the webs of the ties. Where, however, a tie is constructed of the cross section shown in Figs. 11 and 12, the gouging-out of the seating member of the tie is unnecessary, due to the fact that the flanges forming said seating member are of even thickness from edge to edge of said member, and in such 90

cases the opening 41 has its highest point alined with the under surface of the seating member; thus giving the lock key bearing along its full length against the under surface of said seating member. When the lock 5 keys are driven tightly into place, the end portions thereof at opposite sides of the slit 42 are bent at a right angle to the length of the key, as at 44, these bent portions being driven 10 against the outer side of the leg 36 through which the smaller end of the lock key projects; thus firmly securing the fastener member 34 in the splice member and to the tie, without possibility of movement under any 15 vibration to which the track structure may be subjected.

The clamp members 24 are used along the rail lengths or sections, between the splice members, four being employed for each tie, 20 one at each side of each rail. These clamp members differ from the splice members in that they are shorter, and may or may not have the web bearing members adapted to lie against the sides of the web of a rail. In 25 Fig. 2, the inner marginal portions of these clamp members terminate between the edges of the rail flanges and the rail web, and on a straight-lined portion of the track I deem it desirable to use rail clamps of this kind. 30 Clamp members provided with web-bearing portions 33 are employed at the outer side of each rail when curved, but if desired, these clamping members may be employed on both the outer and inner sides of curved rails, or 35 generally along the rails whether straight or curved.

With my improved fastener means I do not consider it necessary to extend the clamp members inwardly beyond a plane passing 40 through each flange of the rail, as it is only necessary that the clamp members overlie the outer marginal portions of the flange. In preferred construction, these clamp members are also provided with shoulders 27 to 45 engage the outer edges of the flanges and with the retainer lugs 30 which pass through the openings 31 in the ties in the same manner as the retainer lugs of the splice members.

Like the splice members, the clamp members 50 are provided with openings 38 through which and the registering openings 39 in the seating members of the ties, the legs or depending portions 36 of the fastener members 34 are passed, and through the openings in 55 these legs the lock keys 40 are passed and fastened in the same manner as those employed for securing the splice members to the ties.

In the modification shown in Fig. 10, the 60 fastener members 34 are solely relied upon to secure the clamp members to the ties, the angular retainer lugs employed in the preferred construction, already described, being dispensed with. When so used, the openings 65 30 in the ties are dispensed with, and this

construction may also be employed in the splice members.

In the modification shown in Figs. 11 and 12, the clamp members are provided with the angular retainer lugs 30 and the ties with the 70 openings 31 into which the retainer lugs are inserted. The ties, however, are constructed without the openings 38, and the fastener members 34' are made somewhat longer so that their depending legs are passed downwardly 75 along the end edges of the clamp member and the side edges of the seating member 16 of the tie. Under this modification the lock keys 40' are somewhat longer and passed through the key holes 37 in said depending legs, and bear against the underside of the seating member along its full width, especially where said seating member is of even thickness from edge to edge, as shown in Fig. 12. The ends of the lock keys are 80 bent over in the same manner as in the preferred construction.

By the use of this invention, all bolts are dispensed with, excepting such as are passed through the upstanding or web bearing portions of the splice members and the webs of two abutting rail sections. Fastener means of novel construction are also employed for splicing rail lengths or sections together and for securing the rails to the ties between the spliced ends of the rail sections, which will not only assure a secure fastening of the rails to the ties, capable of withstanding any jars to which the track structure may be subjected, regardless of the weight or speed of moving loads passing over the same; but which will provide splices at the ends of rail sections sufficiently rigid and secure to permit the bolts passing through the rails to be dispensed with. Such bolts are employed only for increasing the margin of safety and to strengthen the ends of the rail sections when provided with bolt holes, as they usually are. The fastening means provided in conjunction with the tie construction shown and described, guards against spreading of the rails and prevents loosening of the fastening elements under the severest jarring to which the track structure may be subjected.

Having thus described my invention, what I claim is:—

1. The combination with a metallic railway tie having a flat seating member at its upper side upon which rails in spaced relation are placed, of clamping members lying on said seating member at opposite sides of each rail and having portions overlying the flanges of said rails, fastener means bearing against the top of each of said clamping members and having portions extending beneath the plane of said seating member provided with openings, and means underneath said seating member entering said openings to secure said fastener means securely in place.

2. The combination with a metallic railway tie having a flat seating member at its upper side upon which rails in spaced relation are placed, said seating member having a pair of openings at each side of each rail, of clamping members at opposite sides of each rail lying on said seating member and having portions overlying the flanges of said rails, said clamping members having openings therethrough registering with the openings in said seating member, and fastener members each having a portion lying on each of said clamping members and depending portions extending downwardly through the openings in said clamping member and the openings in the seating member registering therewith, said depending portions being provided with key holes, and lock keys passed through said key holes underneath said seating member.
3. The combination of a metallic railway tie having a seating member, a supporting member spaced from and parallel with said seating member and a web connecting said seating member with said supporting member, said seating member having spaced rails lying thereon and having a pair of openings at each side of each rail and said web having openings therethrough transversely alined with the pairs of openings in said seating member, clamping members lying on said seating member at opposite sides of each rail and having portions overlying the flanges of said rail, said clamping members having openings therethrough registering with the openings in said seating member, yoke-like fastener members having horizontal portions lying against said clamping members and depending portions passed through the openings in said clamping members and the openings in said seating member registering therewith, said depending portions being provided with key holes, and a tapered lock pin passed through the key holes in the depending portions of each fastener member and through the opening in the web of said tie alined therewith, said tapering pins being slit at their smaller ends and having portions at opposite sides of said slit bent at right angles to the pin and against the depending portions of said fastener members.
4. The combination of a plurality of railway ties having adjacent ends of two rail sections seated thereon, each railway tie having two spaced pairs of openings between which said rail sections are placed, splice members lying on said ties at opposite sides of said rail sections extending over the flanges of said rail sections and having web-bearing portions lying against opposite sides of the webs of said rail sections, each of said splice members having a plurality of pairs of openings, each pair registering with a pair of openings in one of said ties, yoke-like fastener members having horizontal portions lying against said splice members and depend-

ing portions passed through each pair of openings in said splice members and through the registering pair of openings in said ties, said depending portions having key holes, and keys passed through said key holes underneath fixed portions of said ties.

5. The combination of a plurality of ties, each having a flat seating member and a web extending downwardly from said flat seating member and provided with spaced openings therethrough, the seating members of said plurality of ties having adjacent end portions of two rail sections seated thereon and abutting centrally over one of said ties, the seating member of each tie having a pair of openings transversely alined with each opening in the web of the tie, splice members at each side of and extending over the end portions of said rail sections and having flat portions lying upon the seating members of said ties and portions extending over the flanges of said rail sections and upwardly in contact with opposite sides of the webs of said rail sections, each of said splice members having spaced pairs of openings registering with the pairs of openings in said seating member, bolts passed through the upwardly-extending portions of said splice members and through the webs of said rail sections, and fastener members having depending portions extending through each pair of openings in said splice members and through the registering openings in the seating members of said ties, said depending portions having key holes, and tapered keys passed through the key holes in said depending portions and through the openings in the webs of the ties.

6. Means for fastening a rail to a tie, comprising a rail-engaging member adapted to lie upon a tie and engage the flange of a rail and having two spaced openings, a fastener member having a portion lying against said rail-engaging member and portions at right angles thereto passed through the openings of said rail-engaging member and entering said tie, and means co-acting with said depending portions for drawing said fastener member firmly against said rail-engaging member and for retaining the same on said tie.

7. The combination of a tie having a comparatively thin upper rail seating member across which a rail is laid and through which a pair of openings are formed, a rail-engaging member lying on the seating member of said tie and having a portion overlying the flange of said rail and also a pair of openings extending therethrough registering with the openings in said seating member, a fastener member lying on said rail-engaging member between the openings therein and having depending portions extending through said openings and through the openings in said seating member, and means en-

gaging said depending portions underneath said seating member for drawing said fastener member securely against said rail-engaging member and for securing said fastener member to the tie.

5 8. The combination of a tie having a comparatively thin rail seating member across which a rail is laid, said seating member having two spaced pairs of openings therein between which said rail is placed, a rail-engaging member at each side of said rail lying on said seating member and having a rail-engaging portion overlying a flange of said rail and angular retainer lugs at its 10 outer edge passed through a pair of openings in said seating member, a fastener member having a portion lying flatly against each rail-engaging member and depending portions extending through the openings in said 15 rail-engaging member and a pair of openings in said seating member, and a tapered key passed through the depending portions of each of said fastener members and engaging the under side of said seating member.

20 9. The combination of a metallic tie having a comparatively thin seating member provided with a pair of openings therethrough, a rail supported by said tie, a rail-engaging member engaging said rail to hold 25 the same against said seating member and having angular retainer lugs passed through the openings in said seating member to fasten said rail-engaging member to said rail, and other fastening means in a plane between said angular lugs and the web of said 30 rail serving to additionally fasten said rail-engaging member to said tie, said other means including fastening members, each having a portion lying against a rail-engaging member and depending portions extending 35 downwardly and provided with openings and means entered in and extending from said openings engaging the under side of said seating member.

40 10. The combination with a metallic railway tie having a flat seating member at its upper side upon which a rail is adapted to be placed and a web extending downwardly from said flat seating member and provided 45 with spaced openings therethrough, of clamping members lying on said seating member at opposite sides of said rail and having portions overlying the flanges of said rails, fastener means bearing against each of said 50 clamping members and having portions extending beneath the plane of said seating member provided with openings, and means underneath said seating member passed through said openings and through the openings in the web of the tie to secure the fastener means securely in place.

In testimony whereof, I affix my signature.
CLARENCE S. DAVIS.
